LAUNDRY MACHINE

John Emile and John L. Stephens, Miami, Fla., assignors to Clothes-“A”-Clean Manufacturing Corp., Miami, Fla.

Application March 13, 1956, Serial No. 40,589

Term of patent 14 years

(Cl. D49—1)

FIG. 1.

FIG. 2.

The opposite end of the view in Figure 2 is the same as the visible end. The essential features of our design reside in the portions shown in full lines.

We claim:

The ornamental design for a laundry machine, substantially as shown and described.
